(57) **CLAIM**

I claim the ornamental design for a solar powered insect exterminator, as shown and described.

DESCRIPTION

FIG. 1 is a front elevational view of the solar powered insect exterminator;

FIG. 2 is a rear elevational view;

FIG. 3 is a top view; and,

FIG. 4 is a bottom view.

The broken line showing of environment in the drawings is included for the purpose of illustrating only and forms no part of the claimed design.
